CLAIM

The ornamental design for a bottle, as shown and described.

DESCRIPTION

FIG. 1 is a top, left, front perspective view of a bottle showing my new design;

FIG. 2 is a bottom, left, front perspective view thereof;

FIG. 3 is a rear elevation view thereof;

FIG. 4 is a front elevation view thereof;

FIG. 5 is a left side view thereof;

FIG. 6 is a right side view thereof;

FIG. 7 is a top plan view thereof;

FIG. 8 is a bottom view thereof; and,

FIG. 9 is a cross sectional view, shown in the direction of line 9-9 of FIG. 2.

The evenly dashed broken lines in the drawings illustrate the portions of the bottle that form no part of the claimed design. The dot-dash broken lines define the boundary of the claimed design and form no part of the claimed design.
